[57] CLAIM

The ornamental design for a fishing sinker, substantially as shown and described.

DESCRIPTION

FIG. 1 is a perspective view of the sinker of the invention taken from above and to one side of the sinker; FIG. 2 is a top plan view of the sinker of FIG. 1;

FIGS. 3, 4 and 5 are elevations of the various components of the sinker;

FIG. 6 is a bottom view of the component of FIG. 5; FIG. 7 is a top plan view of two of the components of the sinker;

FIG. 8 is a side elevational view of the two components; FIG. 9 is a bottom view of the two components;

FIG. 10 is a side elevation of a slightly modified form of the design;

FIG. 11 is a side elevation of one of the components of the design of FIG. 10; and

FIG. 12 is a bottom view of the component of FIG. 11.
